MACHINE FOR RIFLING GUNS

Vannevar Bush, Washington, D. C., assignor to
the Government of the United States of Amer-
ica, as represented by the Secretary of War

Application January 23, 1942, Serial No. 427,928

9 Claims. (Cl. 90—28.1)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to the machining of the barrels of guns and in more detail to the rifling of guns having bores of plain or varying form.

It has been found in practice that guns having tapered bores of various forms have certain notable advantages. A desirable form of such a gun has a bore comprising a cylindrical breech portion, an intermediate tapered or conical portion, and a cylindrical muzzle portion with curved transition zones between the tapered portion and each of the cylindrical portions. In a barrel of this type the projectile will be started in a smooth and regular manner, contracted in the tapering portion, and having a section giving it true cylindrical control before it emerges from the muzzle will be more precise in flight than it would be on direct emergence from the conical portion. The difficulty of machining such bores has previously rendered their manufacture impractical and unduly expensive.

It is therefore a primary object of this invention to present a machine for machining the bores of such guns which is sufficiently rapid and precise in operation to be practical from a production standpoint.

It is a further object of my invention to produce a machine for rifling gun bores which is applicable to guns having straight bores, bores of uniform taper, or bores made up of a combination of tapered and cylindrical sections. While the specific description will in general be confined to the latter and more complicated form the modifications required to adapt the device to the simpler forms should be obvious.

The exact nature of the invention as well as other objects and advantages thereof will clearly appear from the description of the preferred embodiment as illustrated in the accompanying drawing in which:

Figure 1 is a diagrammatic side elevation partially in section showing a rifling machine constructed according to my invention.

Figure 2 is a side elevational view partially in section of the plug guide for the rifling machine.

Figure 3 is a side elevational view of the guide taken at right angles to Fig. 2.

Figure 4 is an end elevational view of the larger end of the guide.

Figure 5 is a fragmentary view similar to Fig. 3 showing a modified form.

Figure 6 is a side elevational view of the chain broaching tool.

Figure 7 is a top plan view of the chain broaching tool.

In the preferred practice of the method the gun barrel may be constructed in the usual manner and roughly bored to cylindrical form. By the use of a series of reamers the bore may then be given the desired shape, either conical or composite and having cylindrical end portions and an intermediate conical portion. By following this or any other desired procedure the shape of the bore may be brought to that which is desired for the surface of the lands of the rifling.

A rifling machine preferably constructed as described below is used in forming the rifling grooves in the bore. In the drawing dimensions are distorted for clarity of explanation, lengths being generally foreshortened. Referring to the drawing by characters of reference Figures 2 to 4 show a guide plug 1 slightly longer than the barrel to be machined and having a shape complementary to the bore so that it may fill the bore almost completely. In this plug guide a longitudinal guide channel 2 having a straight inner wall 3 and side walls disposed at a right angle with respect thereto is milled out and ground to finish the surfaces. Operating in this channel are a pair of wedge members 4 and 5. The wedge member 4 has both faces straight and one of these faces is in contact with the inner wall 3 of the guide channel. The end 6 of this wedge member 4 protrudes from the large end of the guide for a purpose as will hereinafter appear. The wedge member 5 has a straight inner surface in contact with the outer surface of the wedge member 4 and the outer face 6 of the wedge member 5 is so formed that it almost corresponds with the shape of the bore, the reason for the slight difference in conformation being hereinafter explained. End plates 7 secured to the guide 1 and bridging a part of the channel 2 retain the wedge member 5 against longitudinal movement in the channel but place no restraint upon radial movement thereof. As shown in Fig. 5 the outer wedge 5 may be supported against longitudinal movement by means of ribs 5a on the side walls thereof adapted to slide in grooves 2a in the side walls of the channel 2. When both of these wedge members are in place there remains outside of them an open channel of substantially uniform depth, the depth of the channel remaining being variable by longitudinal adjustment of the lower wedge member 4.

It should be understood that in practice my invention is not necessarily limited to the use of a plug guide having a shape complementary to the barrel and providing bearing surface for the full length of the barrel. Bearing means need only be provided at the ends of the barrel and may be of any convenient form capable of supporting in the barrel a guide member having therein a guide channel 2 of the specified form.

It is through the guide channel that the broaching tool described below is operated.

A chain broach shown in place in Fig. 1 and shown specifically in Figs. 6 and 7 is adapted to operate in the portion of the channel remaining outside of the wedge members 4 and 5. The chain broach comprises a plurality of links 8, smooth on their sides and of a width such as to fit in the channel with a smooth sliding engagement. At spaced intervals in the chain links 13 will be inserted, the links 13 being each equipped with a cutting edge 14 similar in shape to that commonly used on broaching tools. The bottom face of each of the links is formed with rounded projecting ends 10 adapted to ride on the outer face of the wedge 5. The side faces of each of the links 8 and 13 are recessed as best shown in Fig. 6 and connecting bars 11 are received therein and connected to the links by coupling pins 12 forming a continuous chain slidable through the channel.

At this point it is convenient to describe in detail the shape of the outer face 6 of the outer wedge 5. In determination of this shape it will be convenient to consider that the plug guide 1 has been tightly inserted in the smooth bore of the unrifled gun. In this condition if a link 13 having a cutting edge 14 is inserted in the guide channel 12 on the outer face of the wedge 5 and the inner wedge 4 moved inward until the cutting edge 14 just touches the inner surface of the gun bore the shape of the outer face 6 should be such that the link 13 may be moved the full length of the channel 2 and the edge 14 will contact the wall of the gun bore at all points along the path. If the gun bore were cylindrical, or tapered uniformly throughout it is apparent that this path would be a straight line parallel to the surface of the bore. When, however, there are cylindrical and conical sections having transition curves in the bore to be machined the shape of the outer face 6 will not quite duplicate that of the longitudinal section of the bore on account of the finite size of the link. The shape is, however, readily determined and milled by a procedure similar to that used in making cams. In order that the chain may enter the channel without binding, the side walls of the channel external to the section of the guide embraced by the barrel may be slightly relieved.

A preferred form of the assembled rifling machine, with details omitted, is shown in Fig. 1. The plug guide is preferably mounted vertically, large end down on a rigid base 15 and the upper end may be steadied by means of an arm and detachable clamp, not shown. The complete chain broach, in endless form, is mounted on a pair of sprockets 16 driven by suitable gearing 17 and so lined up that the chain may be fed directly through the guide channel 2. Around the lower part of the plug guide and coaxial therewith is a rotating collar 18 arranged to be driven by a worm 19 and ring gear 20 in synchronism with and at a predetermined speed in relation to the gearing driving the broaching chain. The pitch of the rifling is dependent upon this speed relation. This rotating collar is supported on bearings 21 capable of supporting end as well as radial loads and is provided with a socket 22 adapted to embrace the end of the barrel. Set screws 23 or other equivalent means may be provided to insure that the barrel rotates with the collar. The inner wedge 4 has its large

end projecting downwardly below the rigid base 15 and is notched at 24 and so arranged that it can be given a step-like intermittent feeding motion by a lever and pawl 25 or by other known intermittent feed mechanisms. In order to commence the rifling operation the broaching chain may be opened at a readily detachable link and the barrel slipped over the plug guide, breech end down and resting on the rotating collar 18 to which it is clamped to positively receive rotation therefrom. The collar should be so disposed in relation to the barrel and guide that it will support the barrel in a position in which the bore of the barrel will fit over the guide with allowance for a film of lubricant therebetween. The inner wedge being in its extreme retracted position the cutting edges 14 will not contact the surface of the bore and the broaching chain may be restored to endless form on the sprockets. Depending upon the pitch of the rifling gearing of the desired ratio will be provided between the worm gear 19 and driving gear 17 for the sprockets 16.

At intervals after starting the machine the ratchet mechanism 25 operates, advancing the lower wedge and feeding the cutting edges nearer the surface of the bore. When the wedge has been sufficiently advanced the leading cutting edge will cut a narrow groove on the inside of the bore, the groove being in helical form as the barrel is being rotated while the cutter advances vertically. Due to the rotation of the barrel the cutting edge that follows will cut, not in this same groove, but will take the beginning cut for the next adjacent groove of rifling. Succeeding cutting edges commence each succeeding groove until a cutting edge has traversed each of the grooves. Following the last of such cutting edges is a section of the chain of slightly greater length than the length of the bore in which there are no cutters. When the last cutting edge has left the bore the feeding device operates to advance the inner wedge and the procedure is then repeated, the cutting edges now deepening and widening each groove in turn. The process of alternate cutting and advancing the cutters continues until the job is finished. It should be noted that several edges are thus cutting simultaneously and that the number of cutting edges should be equal to the number of grooves or some exact multiple thereof. The cutting edges may be mounted at an angle on the links so that the resultant direction of the cutting motion is nearly perpendicular to the cutting edge. It is preferable to cut a narrow groove first and then to widen it to final shape as it is deepened. Obviously, the form given the cutting edge will determine the shape of the groove.

Normally the speed of the cutting chain should be about 30 feet per minute, and at the beginning of the run the feed ratchet should be so adjusted that the depth of cuts will be about .004". These values will, of course, be dependent upon the physical characteristics of the material employed in the gun barrel but in the ordinary case the job of rifling a gun of small size should not take more than ten minutes after the set-up is completed.

Since the angle between the cutting edge and the groove being cut varies slightly as the edge is moved through the bore, the cutting tool should be given such rake and clearance all around its active portion that proper cutting action will be obtained in spite of the change in angle. Due to

this same change of angle the groove will not be of quite the same cross sectional shape throughout but as the barrel engaging portion of the shell is being compressed radially as it progresses through the bore the variation in groove section will not allow gas leakage therethrough.

If it is desired to vary the depth of the groove along the bore, this can be accomplished by varying the shape of the outer face 6 of the outer wedge from that previously detailed, which results in a groove of uniform depth.

It is also possible to control the width of grooves of regular dimensions, say a groove of generally right angular form having rounded corners. To do this the grooves may first be cut as described above, then the gear ratio changed to slightly alter the pitch, and the grooving repeated, being sure of initial registry. This will alter the width of the groove as it passes along the bore.

Various other refinements are possible, but for the usual case it is believed that grooves of uniform or slightly decreasing depth are preferable, and that a slight narrowing of the width of the groove, in proceeding from the breech of the muzzle, is desirable.

In guns of conical bore there is a deformation of the barrel engaging portion of the shell as the shell progresses through the gun, and this may reach extreme limits. This radial compression will occur at both the grooves and the lands, accompanied by longitudinal extension of the barrel engaging portion of the shell. Whether the depth of the grooves should be uniform throughout, or whether, for example the depth of groove should be maintained proportional to the diameter at all points is a matter upon which authorities differ. As described above this method can produce any desired relationship in width and depth of grooves in proportion to diameter. This method can also be used in the rifling of straight conical or cylindrical bores, the outer guide wedges only requiring to be formed in a shape substantially complementary to that of the bore to be rifled.

I claim:

1. Apparatus for rifling the bore of a gun comprising spaced cutters connected in chain fashion, means to guide said cutters in a path substantially parallel to the longitudinal profile of the surface of said bore, said path being constrained by said guiding means to a plane including the axis of the bore, means to advance said cutters along said path, and means to rotate said barrel about its axis as said cutters are advanced whereby said cutters trace helical paths in the wall of said bore.

2. Apparatus for rifling the bore of a gun barrel comprising a body of a length at least as great as that of the barrel and adapted to be inserted therein, a longitudinal guide channel in said body, a plurality of spaced cutters connected in chain fashion and slidable in said guide channel, adjustable means to place said cutters in cutting relation with the wall of said bore when said body is inserted in the barrel, means to advance said cutters longitudinally in said channel, and means operating in geared relation to said last mentioned means adapted to rotate the barrel about its axis as said cutters are advanced longitudinally thereof.

3. Apparatus for rifling the bore of a gun barrel comprising a body of a length at least as great as that of the barrel and adapted to be inserted in

said bore, means on said body adapted to support said barrel for rotation about the axis of the barrel while the barrel is surrounding said body, a longitudinal guide channel in said body, a plurality of spaced cutters connected in chain fashion and slidable in said guide channel, adjustable radial guide means in said channel inside of said cutters, means to advance said cutters longitudinally in said channel, and means operating simultaneously and in relation to said last mentioned means adapted to rotate said barrel about its axis as said cutters are advanced longitudinally of said axis whereby said cutters trace helical paths in the wall of said bore.

4. The apparatus described in claim 3, the means on said body adapted to support said barrel comprising portions of said body of a size and shape adapted to engage the wall of said bore.

5. The apparatus described in claim 3, said radial guide means comprising a pair of wedge members in said channel, one of said wedge members being longitudinally adjustable and the other of said wedge members being longitudinally fixed but radially free whereby longitudinal adjustment of said adjustable wedge member may vary the depth of the said guide channel outside of said wedge members.

6. The apparatus described in claim 3, said radial guide means comprising a guide member extending at least the full length of said channel, and a track surface on said guide member upon which said spaced cutters are slidably, the longitudinal profile of said track surface being such that the path followed by the cutting edges of said cutters as they are moved longitudinally thereof will be substantially parallel to the longitudinal profile of the surface of the bore in which said body is inserted.

7. Apparatus for rifling the bore of a gun barrel comprising a body having a length at least as great as the barrel and adapted to be inserted in the bore of a gun barrel, a collar surrounding and rotatably mounted on an end of said body, adapted to engage a gun barrel to rotate the same about said body, a longitudinal guide channel in said body, sprockets rotatably mounted on the ends of said body in tangential alignment with said guide channel, means to regulate the depth of said guide channel, an endless chain of links slidable through said channel and engaged on said sprockets, a plurality of cutters on spaced links of said chain, means to rotate said sprockets to draw said cutters through said guide channel, and means operating simultaneously and in geared relation to said last mentioned means to rotate said collar whereby said cutters may be caused to trace helical paths on the walls of said bore.

8. The apparatus described in claim 7, said body comprising a plug-like member having a size and shape complementary to the shape of the bore in the barrel to be rifled.

9. The apparatus described in claim 7, said cutter carrying links being equal in number to an exact multiple of the number of grooves to be formed in the bore, a section of said chain of length at least as great as said barrel following said cutter carrying links, the links of said section being without cutters, and intermittent feed means adapted to decrease the depth of said guide channel during each interval that said section is engaged in said channel.

VANNEVAR BUSH.
